UNITED STATES PATENT OFFICE.

GEORGE H. BARBOUR, OF PITTSBURGH, PENNSYLVANIA.

RAILWAY-TRACK CONSTRUCTION.

1,144,164.

Specification of Letters Patent. Patented June 22, 1915.

Application filed March 5, 1912. Serial No. 322,644.

To all whom it may concern:

Be it known that I, George H. Barbour, a citizen of the United States, residing at Pittsburgh, in the county of Allegheny and State of Pennsylvania, have invented a new and useful Improvement in Railway-Track Construction, of which the following is a full, clear, and exact description, reference being had to the accompanying drawings, forming part of this specification, in which—

Figure 1 is a view showing one form of my improved track rail in cross section and one form of rail tie and fastening in elevation. Fig. 2 is a view showing the same rail in side elevation and the tie in cross section. Fig. 3 is a side elevation of the tie of the preceding figures with the rail and fastenings removed. Fig. 4 is a perspective view of one form of one of my improved fastenings. Figs. 5 and 6 are views similar to Figs. 1 and 2, respectively, but showing a modification. Fig. 5 also illustrating one method of applying the fastenings to the rail and ties. Fig. 7 is a rear view of the lever shown in Fig. 5. Fig. 8 is a detail sectional view illustrating one step in the manufacture of my improved rail head. Fig. 9 is a perspective view of one form of the spacer or spreader used between the rail base members. Figs. 10 and 11 are views partly in vertical cross section and partly in elevation, illustrating two other forms of compound rails and also showing two different clamping means. Figs. 12 and 13 are views similar, respectively, to Figs. 1 and 2, but showing another form of compound rail, rail tie and fastenings. Fig. 14 is a perspective view of one of the fastenings of Figs. 12 and 13. Fig. 15 is a view partly in vertical cross section and partly in elevation showing another way of clamping the rail parts. Fig. 16 is a view similar to Fig. 13, but showing the rail insulated from the tie and also showing a modified form of rail. Figs. 17 and 18 are views similar, respectively, to Figs. 1 and 2, showing a rail splice applied. Fig. 19 is a view similar to Figs. 17, showing a still further modification. Figs. 20 and 21 are detail respective views of the bolt and washer shown in Figs. 12 and 15. Figs. 22, 23 and 24 are cross sections showing three other modified forms of compound rails. Figs. 25 and 26 are cross sec-

tional views showing still other forms of the compound rail and also showing the application of clamping means thereto, and Fig. 27 is a view similar to Fig. 1 and showing the fastenings of Fig. 1 applied to an ordinary T-rail.

My invention has relation to a system of railway track construction.

Railway tracks as constructed at the present time have not been increased in strength in proportion to the increased duty imposed upon them, and in the endeavor to increase the wearing qualities of the rail heads, the ductility, and hence the ability of the rails to stand shocks and fatigue has been sacrificed. While it has been proposed to construct rails with separate heads of various kinds, none of the proposed constructions, in so far as I am aware, have the head rigidly secured and at the same time readily and cheaply attachable and detachable. The prior constructions also require the employment of complicated power machinery and of methods which are foreign to those familiar to the present section crews.

One object of my present invention is to provide a track system, comprising rails having separate heads of hard material secured to bases of more ductile quality; together with improved splices, ties and fastenings, all the parts being held or secured in the proper relation or adjustment to each other by the elasticity of the material of the parts themselves, thereby reducing to a considerable degree the objectionable rigidity in present track systems of the heavier types.

A further object of my invention is to provide a system of track construction of this character, such that its installation, renewal and repair can be readily carried out by section crews organized as at present and equipped with a few cheap and simple tools closely approximating the present pinch bars and wrenches.

My invention also contemplates the provision of a compound rail which is in itself of improved character and of ties and fastening devices also of novel character.

The exact nature of my invention will be best understood by reference to the drawings in which I have shown various modifications and which will now be described, it being premised, however, that the invention is susceptible of various other modifications

within the scope of the broader claims appended hereto.

Referring first to that form of my invention shown in Figs. 1 to 4, inclusive: The track rail shown in these figures consists of a separate head member 2 of such character of steel as will possess the best wearing qualities; together with the two base forming members 3, which may be of a softer and 10 more ductile steel, corresponding more nearly to ordinary structural steel. The head 2 is formed with a longitudinal recess 4 on its under side; the side wings 5 of which have the undercut beveled inner surfaces 6. 15 This head may be readily rolled in the form shown in cross section in Fig. 8 with the flanges 5 projecting somewhat laterally; and these flanges may be subsequently closed in to the position shown in Fig. 1, by any sufficient bending operation. This method will avoid the difficulty of rolling a head member having the finished cross section shown in Fig. 1. Each of the members 3 has an outwardly turned base flange 3^a at its lower 25 end, an intermediate vertical web portion, and a head portion 3^b at its upper end. The head portions 3^b, have the inward projections 3^c, and also the upward projections 3^d, which fit within the recess on the under side 30 of the head and have the beveled outer surfaces 3^e which are designed to be interlocked with the beveled inner surfaces of the side walls or flanges of said recess. The two members 3 are set up in inclined relation 35 with their webs separated some distance and their head portions 3^b sufficiently separated to permit of the insertion, at suitable intervals, of a spacer or spreader 7 (one of which is shown in detail in Fig. 9). The rail members 40 can be readily assembled in this position and placed upon the ties 8. These ties are shown as being of metal of a T-shaped cross section, the top arm of the T having a depending flange 8^a at each edge. 45 These flanges are cut away or notched at intervals, as shown at 9.

The members of the compound rail are firmly locked in their assembled positions and are also securely held to the ties 8 by 50 means of fastenings which, when applied, place the parts in tension so that the fastening is obtained by the elasticity of the various members themselves. In the form shown in these particular figures, the fastenings consist of a series of clips, each of which has a lip 10 at one end for engagement with the base flange 3^a of one of the members 3; an adjacent lateral lip 11 for engagement with one of the recesses or 55 notches 9, and a similar lateral lip 12 at its other end for engagement with another notch or recess 9. These clips are applied alternately from opposite sides. That is to say, adjacent clips are reversed end for end, as shown in Figs. 1 and 5. A punch or

clamp bar 13 having a toe 13^a and a heel 13^b is then applied to the free end of each fastening to force its lip 12 downwardly and into engagement with one of the notches 9, its other lip 11 having been engaged with an adjacent notch 9. The fastenings also act as levers in conjunction with the punch bar in springing the rail and tie members into their final assembled positions. It will be readily seen that during this operation a tension is placed on the members 3, causing them to spring their base flanges 3^a toward each other, the spreaders 7 acting as levers for this springing action. Consequently, when the fastenings have been secured in the manner described, all the parts are in tension and are secured by their inherent elasticity. This does away with the necessity for separate fastening members of a character likely to work loose in service and provides a suitable means for securing the members of the compound rail, and at the same time securing such compound rail to the ties.

In the construction shown in Figs. 5 and 6, the base forming members 3 of the rail 92 are of somewhat different form at their upper ends, the inward projection of their heads being absent; and instead of spacers, such as shown in Fig. 1, between said inwardly projecting heads, I provide spacers 85 15 interposed between the web portions of the two members and having reduced end portions 16 which fit in the notch 9 of the webs. In these figures also the ties 8 are shown as of inverted U-shape in cross section, their flange portions having notches 18 for the tips 10 of the fastenings 17. These fastenings are of the angular type first described and act in substantially the same manner.

In Fig. 10, the compound rail is of substantially the same construction as in Fig. 1, except that the spacers 7 are omitted and the inwardly projecting head portions 3^b of the base-forming members 3^a bear directly upon each other. The main purpose of employing spacers is to insure a proper fulcruming action notwithstanding considerable variation and inequalities in the rail members. When fillers are used they may be provided in inserted spaces. This figure also illustrates a suitable clamping tool 325 applied to the members 3^a for the purpose of springing their base portions downward and holding them in this position while the rail is secured to the ties. Any suitable securing means may be employed for this purpose, such for instance, as the keys 14, shown in Fig. 19. As soon as these keys have been inserted and secured the clamping tool 325 can be removed, leaving the rail members secured to the ties under tension.

Fig. 11 shows substantially the rail of Fig. 1, with a different form of clamping tool 330 applied thereto to spring the rail into the

160 forwardly. In this form I have also shown L-shaped spacers 25 instead of the T-shaped spacers 7 of Fig. 1. This rail may also be secured to the ties by any suitable

165 means.

170 In Figs. 12 and 13, the head member 26 of the rail is shown as having a depending longitudinal rib projection 27 on its bottom which is arranged to interlock with the grooved 175 surfaces 28 of the base holding members 29. The members of the rail are secured together 180 by means of bolts 30. Each of these bolts 185 has a head 31 at one end and a smaller head 32 at the opposite end, the latter being capable of being passed through openings 33 in 190 the webs of the members 29. These bolts are 195 of sufficient length so that after they have 200 been inserted slotted washers 34 can be 205 dropped behind the smaller heads 32 and 210 between said heads and the web and the adjacent member 29. By means of a spreading 215 tie 25 (shown at Fig. 15) the two members 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ties is insulated, as indicated at 43; the insulation is placed at both sides of the member 42 so that no currents can pass from the rails to the ties.

In Figs. 17 and 18 I have shown the application of a splice bar jointed to the compound rail. The rail tie and fastenings shown in these figures are substantially the same as in Figs. 1 and 2. 44 designates the splice bars and 45 the securing bolts therefor.

Fig. 22 shows a modified form of the compound rail in which the head 46 is secured in substantially the same manner as in Fig. 1, but the spacers or spreaders 47 are formed with heads 48 which further support the rail head 46.

Another way of providing additional support for the rail head is shown in Fig. 23, in which the head 49 has a central longitudinally depending rib 50 which bears on the abutted heads 51 of the base forming members 52 of the rail.

Fig. 24 shows a construction generally similar to that of Fig. 1, but with the section 29 taken through the splice bars and with a central filler and reinforcement 53 of a different character from those heretofore described. This filler and reinforcement has a vertical web portion intermediate the webs 23 of the base forming members 54. At the upper edge of the web the filler has a head 55 and at its lower edge a base flange 56 with beveled surfaces 57 which contact with similarly beveled surfaces 58 on the base flanges 103 of the members 54.

Fig. 25 shows a compound rail very similar to that shown in Fig. 12, but with insulation 59 interposed between the head 59 and the base forming members 60. The parts are secured by bolts and washers 61, similar to those shown in Fig. 23. The members 60 are designed to be expanded to put the bolts 61 under tension by means of a suitable expanding appliance 62, whose legs engage openings 63 in the base flanges of the members 60. By means of this device the portions 60 can be expanded to a sufficient extent to permit the insertion at intervals and especially at the splices of the wedge members 61. These members act in general in the same manner as those shown in Fig. 14; but in this particular form the tie engaging lips are not present and the rail is designed to be secured to the tie by any suitable means, such for instance, as the keys shown in Fig. 19.

Fig. 26 illustrates a construction very similar to that shown in Fig. 10, but with insulation 65 interposed between the head 65 and the lower members of the rail. In this construction the lower members 66 instead of being held by bolts which are put under tension by expanding the lower members of the rail, are secured at intervals and espe-

100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

cially at the splices by means of the flanged base clips or plates 67. The members 66 may be sprung inwardly to permit of their engagement with these clips by a clamping device, such as indicated at 68 of this figure.

Fig. 27 shows the application of the tension fastenings of Fig. 1 to an ordinary T-rail 69. The tie 70 shown in this figure is also similar to that shown in Figs. 1, 2, 10 and 3. The fastenings 71 are similar to those shown in Fig. 1 and are applied substantially as shown and described in connection with Figs. 1 and 2.

The advantages of my invention will be apparent to those skilled in the art. It provides a compound rail, the members of which can be readily rolled and formed, the head being of a different and more durable quality of steel from the remaining portions. The 20 parts of the rail can be readily assembled and are in each case securely interlocked and held in assembled relation by elasticity or tension imparted to the base forming members of the rail. By relieving this tension 25 the heads can be quickly removed and replaced when necessary. The fastening devices are also extremely simple and positive in their character, depending upon the elasticity of the parts. The use of fastening 30 means of a character to become loose in service is avoided. The invention lends itself to effective insulation of the rails or rail heads and possesses numerous other advantages.

I claim:

1. A compound rail, having its members sprung into interlocking engagement with each other, and means engaging said members to secure them in such engagement, said means having hooks for securing engagement with the rail supporting ties and also forming fastenings for securing the rail to its supporting ties; substantially as described.

2. A compound rail, comprising a head forming member and two web and base forming members, and means engaging the upper and lower portions of the last-named members at intervals to hold them interlocked with the head forming member and also securing the rail to a support; substantially as described.

3. A compound rail, comprising a head forming member and two web and base forming members, and means engaging the base forming portions of the last-named members at intervals to hold them interlocked with the head forming member, said means having hooks for engagement with a support and forming fastenings for securing the rail to a support; substantially as described.

4. A compound rail, comprising a head forming member and two web and base forming members, the latter being sprung 35 into interlocking engagement with the head

forming member, and means engaging the upper portions of the web and base forming members at intervals to hold them interlocked with the head forming member; substantially as described.

5. A compound rail, comprising a head forming member and two web and base forming members, the latter being sprung into interlocking engagement with the head forming member, and means engaging the base forming portions of the web and base forming members at intervals to hold them interlocked with the head forming members, said means having hooks forming fastenings for securing the rail to a support; substantially as described.

6. A compound rail, comprising a head forming member and two web and base forming members, there being means at intervals on which the webs can fulcrum to spring them into interlocking engagement with the head, and fastening means engaging the base forming members at intervals to secure them in such sprung interlocking engagement with the head; substantially as described.

7. A compound rail, comprising a head forming member and two web and base forming members, there being means on which the web and base forming members can fulcrum to spring them into interlocking engagement with the head, and fastening means engaging the base portions of the web and base forming members to secure them in such sprung interlocking engagement with the head, said fastening means having a hook connection to the tie for securing the rail to its support; substantially as described.

8. A compound rail, comprising a head forming member and two web and base forming members, there being means on which the web and base forming members can fulcrum below the head to spring them into engagement with the head, and means for securing the rail to a supporting tie, said means having a hooked engagement with a rail supporting tie and thereby acting to hold the parts of the rail in their sprung interlocked engagement; substantially as described.

9. A compound track rail, comprising a head forming member and two web and base forming members sprung into interlocking engagement with the head forming member, and fastening means engaging the base portions of the web and base forming members at intervals to hold the said members interlocked, said fastening means also being sprung into securing engagement with a rail supporting member and having a hooked engagement therewith; substantially as described.

10. A compound rail, comprising a head forming member and two web and base

- forming members sprung into interlocking engagement with the head forming member, the head forming member having three points of support on each of the web and base forming members, and fastening means engaging the base portions of the web and base forming members at intervals to hold them in such engagement with the head forming member; substantially as described.
- 10 11. A compound rail, comprising separable head and base forming members having interlocking portions, said base forming members having engagements between them and having means whereby stresses are produced in said members to interlock them with the head forming member, and lever fastenings engaging said base forming members and also engaging the supporting tie for the rail, said fastenings having means 15 acting to maintain such stresses; substantially as described.
12. A compound rail, comprising separable head and base forming members having interlocking portions, and fastenings for 20 securing the rail to a tie, said fastenings having means acting to maintain a stress in the base forming members for holding them interlocked with the head member, and also having hooked tie engaging means; substantially as described.
13. A compound track rail, comprising separable head and base forming members having interlocking portions, intermediate fulcruming members at intervals interposed 25 between the base forming members, and means independent of the intermediate fulcruming members for causing a fulcruming action on the base forming members to secure their interlock with the head forming 30 member; substantially as described.
14. A compound track rail, comprising separable head and base forming members having interlocking portions, and bolts connecting the base forming members and having 35 means whereby the bolts and said members are placed in tension to interlock them with the head forming member, together with fastenings for securing the rail to a tie, said fastenings having wedge means acting to maintain such tension; substantially 40 as described.
15. A compound track rail, comprising separable head and base forming members and having interlocking portions, and bolts 45 connecting the base forming members and having means whereby the bolts in said members are placed in tension to interlock them with the head forming members, together with fastenings for securing the rail 50 to a tie, said fastenings having wedge means acting to maintain such tension, and also
- having tie engaging means; substantially as described.
16. A compound track rail, comprising separable head and base forming members 55 having interlocking portions, bolts connecting the base forming members and having means whereby the bolts and said members are placed in tension to interlock them with the head forming member, and fastenings 60 for securing the rail to a tie, said fastenings having means acting to maintain such tension; substantially as described.
17. A compound track rail, comprising separable head and base forming members 65 having interlocking portions, bolts connecting the base forming members and having means whereby the bolts and said members are placed in tension to interlock them with the head forming member, and fastenings 70 for securing the rail to a tie, said fastenings having means acting to maintain such tension and also having tie engaging means; substantially as described.
18. A compound rail, comprising separable head and base forming members having interlocking portions, lever fastenings 75 engaging said members to secure them in such engagement, said lever fastenings having hooks for securing engagement with the rail supporting ties and forming fastenings 80 for securing the rail to its supporting ties; substantially as described.
19. A compound rail, comprising separable head and base forming members having interlocking portions, lever fastenings 85 engaging said members to secure them in such engagement, said lever fastenings having hooks for securing engagement with the rail supporting ties and forming fastenings 90 for securing the rail to its supporting ties, together with means for insulating the head from the base forming members of the rail; substantially as described.
20. A compound rail, having lever fastenings for securing the rail to a tie, each of said fastenings having a plurality of hooks arranged to engage notches in vertical portions of the tie; substantially as described.
21. The combination with a rail and its 105 supporting tie, of lever fastenings for securing the rail to a tie, each of said fastenings having a plurality of hooks, and the tie having vertical portions provided with notches to receive said hooks; substantially 110 as described.
- In testimony whereof, I have hereunto set my hand.
